UNITED STATES PATENT OFFICE.

PHILIP J. MITTEN, OF PHILADELPHIA, PENNSYLVANIA, ASSIGNOR TO THE NEAR SIDE CAR COMPANY, OF NEW YORK, N. Y., A CORPORATION OF NEW YORK.

DOUBLE-DECK VEHICLE.

1,102,602.

Specification of Letters Patent. Patented July 7, 1914.

Application filed January 13, 1913. Serial No. 741,710

To all whom it may concern:

Be it known that I, PHILIP J. MITTEN, a citizen of the United States, residing at Philadelphia, in the county of Philadelphia, 5 and State of Pennsylvania, have invented certain new and useful Improvements in Double-Deck Vehicles, of which the following is a specification, reference being had therein to the accompanying drawing.

10 This invention relates to double deck vehicles and more particularly to a motor-driven bus of this type.

The invention has two main objects.

One object is to provide such a vehicle 15 having a maximum seating capacity and the other object is to provide such a vehicle which can be controlled entirely by a single officer, that is, the official who acts as chauffeur will also collect the fares and control 20 the entrance and exit of passengers to and from the bus.

It is also an object of the invention to provide a vehicle of this kind in which the lower deck may be entirely inclosed, by 25 providing doors for the entrance and exit passageways, which are under the control of the officer in charge, and by providing a door to close the stairway leading to the upper deck.

30 It is a further object of the invention to provide the car with the entrance and exit passageways both at the front end; to arrange the stairway leading to the upper deck at the rear end of the bus and at one side 35 of the center thereof, thus leaving a large amount of space at the rear ends of both the upper and lower decks which is available for seats.

In the accompanying drawings, Figure 1 40 is a side elevation, partly broken away, of a bus embodying my invention; Fig. 2 is a top, plan view of the upper deck; and Fig. 3 is a transverse sectional view of the bus showing the lower deck in plan.

45 In these drawings I have illustrated my invention as applied to a motor driven bus, the supporting frame of which is shown at 1 and may be of any suitable character and the propulsion of which may be accomplished in any suitable manner. Mounted 50 upon the frame 1 is the body portion of the bus which comprises a lower deck 2 and an upper deck 3. In the present instance the lower deck is closed and the upper deck is 55 entirely open, but it will be obvious that this

is not an essential part of the invention and that the decks may be either open or closed, as may be desired. In the construction here shown the lower deck is provided at its forward end with both an entrance and an exit 60 passageway, the entrance passageway being arranged adjacent to the station of the chauffeur or other official in charge of the motive power. A passageway leads from the entrance and exit passages rearward to 65 a stairway leading to the upper deck, this stairway being here shown as a spiral stairway and being arranged at one side of the center of the bus, thus leaving a large portion of the rear wall of the vehicle and that 70 side of the vehicle opposite the stairway available for seating purposes. Likewise, the stairway opens into the upper deck at one side of the center thereof and thus leaves a considerable portion of the rear end and 75 side wall of this deck available for seats.

The particular construction and arrangement of the several parts of the vehicle may be varied as circumstances may demand, but for the purpose of illustration I have here 80 shown the lower deck of the vehicle as provided at its forward end and on one side of the center line thereof with an entrance passageway 4 and an exit passageway 5, the two 85 passageways being divided by a barrier or rail 6 extending from a point adjacent to the side of the vehicle to a point near the center of the body portion thereof. Arranged adjacent to the entrance passageway and in the present instance at that side of the vehicle 90 opposite the entrance and exit passageways is a station or seat 7 for the official in charge and arranged adjacent to this seat is the steering and controlling mechanism for the vehicle, as shown at 8. Further, if desired, 95 a fare box 9 may be mounted adjacent to the officer's station and to the entrance passageway. In this manner the officer in charge is enabled to perform the duties both of the 100 chauffeur or driver for the vehicle and of the conductor or fare collector. Further, the entrance and exit passageways are provided with closures which may be operated by the officer from his station. As here shown, each passageway has at its outer end a folding door 10 and folding step 11 which are connected, in a known manner, with operating handles 12 arranged adjacent to the officer's station. 105

The connections between the operating de- 110

vices and the doors and steps need not be here described in detail but it is sufficient to note that they are such that either door and the corresponding step may be simultaneously operated to open or close its passageway independently of or in unison with the other door and its step. The particular arrangements of the doors and of the door and step operating devices are not a part of this invention but are fully shown and described and the novel features thereof claimed in certain applications filed by Ralph T. Senter and assigned to the assignees of the present invention, to wit, application Ser. No. 638,635, filed July 5th, 1911, and divisional applications, Ser. Nos. 681,544 and 681,545, filed April 17th, 1912. Within the body of the vehicle and adjacent to the ends of the entrance and exit passageways the vehicle is provided with lengthwise seats 13 and 14, thus affording a broad entrance into the body portion of the vehicle and avoiding any congestion when large numbers of passengers are entering or leaving the vehicle at the same time. In the central portion of the vehicle the seats extend crosswise, as indicated at 15, and are spaced apart in the usual manner to form a passageway 16 which leads from the entrance and exit passageways to the stairway at the rear of the vehicle. The rear portion of the lower deck of the vehicle is here shown as entirely closed, although this is not essential to an embodiment of the invention. The crosswise seats terminate at some distance from the rear end wall of the vehicle and a stairway 17, which is here shown as spiral in form, is arranged in the extreme rear part of the vehicle at one side of the longitudinal center thereof, thus occupying a minimum amount of space and enabling a considerable portion of the rear wall and that portion of the side wall of the vehicle opposite the stairway to be utilized for a seat 18. The arrangement of this seat is such that while it will accommodate several passengers it will not, when occupied, obstruct the free passage of passengers to and from the stairway. A similar arrangement exists at the rear end of the upper deck of the vehicle except that the portion of the seat, 19, which extends along the rear wall thereof is somewhat shorter than the corresponding portion of the seat 18, this being necessary in order to allow the passengers to pass from the step of the stairway 17 onto the floor of the upper deck. That portion of the upper deck forward of the stairway is provided with crosswise seats 20 of the usual construction and arrangement. As here shown the upper deck is inclosed by a railing 21, but obviously any suitable inclosure may be provided.

It is desirable that means should be pro-

vided for entirely inclosing the lower deck 22 of the vehicle to prevent drafts and to exclude rain and wind. The front end, of course, will be entirely closed by the doors 10 and in order to close the rear end I have inclosed the stairway by means of a wall 22 70 and have arranged the door 23 at the lower end thereof to entirely close the same. This door is preferably a sliding door and is arranged to slide into a pocket 24 arranged beneath the top of the stairway. 75

It will be apparent from the drawings and the foregoing description that the vehicle has a very large seating capacity and will in fact seat a greater number of passengers than any other similar vehicle of the same proportions. Further it will be apparent that a single official has control of the entire vehicle, both the motive power and the collection of fares. Moreover, it will be apparent that the arrangement is such as to provide a minimum of interference in the entrance and exit of passengers and that the lower deck can be entirely inclosed if it should be desirable, as in rough weather. 90

While I have shown and described the invention as embodied in a motor driven bus it will be obvious that the invention is not limited to this class of vehicles but is capable of a broad application. Further, while I have shown and described one embodiment of the invention it will be understood that this has been chosen for the purpose of illustration only and that I do not desire to be limited to the details of construction shown and described, for obvious modifications will occur to a person skilled in the art. 95

Having thus fully described my invention, what I claim as new and desire to secure by Letters Patent, is:— 100

1. A vehicle comprising a lower deck and an upper deck, the lower deck having at one end both an entrance passageway and an exit passageway, a stairway arranged within the vehicle at the other end of said lower deck, and a passageway connecting said entrance and exit passageways with said stairway. 110

2. A vehicle comprising a lower deck and an upper deck, the lower deck having at one end both an entrance passageway and an exit passageway and having its other end closed, a stairway arranged within said vehicle at the closed end of said lower deck, 120 and a passageway connecting said entrance and exit passageways with said stairway.

3. A vehicle comprising a lower deck and an upper deck, the lower deck being provided at one end with both an entrance and an exit and having its other end closed, a stairway arranged at the closed end of said lower deck and at one side of the center

thereof, and a passageway connecting said stairway with said entrance and said exit.

4. A vehicle comprising a lower deck and an upper deck, the lower deck being provided at one end with both an entrance and an exit and having its other end closed, a stairway arranged at the closed end of said lower deck and at one side of the center thereof, and a seat extending across the closed end of said lower deck and along that side thereof opposite said stairway, and a passageway connecting said stairway with said entrance and said exit.

5. A vehicle comprising a lower deck and an upper deck, said lower deck being provided at its front end with an entrance and an exit, doors to open and close said entrance and said exit, a stairway at the rear end of said lower deck leading to the upper deck, and a door to close said stairway, thus enabling said lower deck to be entirely closed.

6. A vehicle comprising a lower deck and an upper deck, said lower deck being provided at its front end with separate entrance and exit passageways and having longitudinal seats arranged along that portion of the vehicle adjacent to the inner ends of said passageways, crosswise seats arranged in the rear of said longitudinal seats, a stairway arranged in the rear of said crosswise seats and at one side of the center of said vehicle, and a seat extending along the rear wall of said vehicle and that portion of the side wall thereof opposite said stairway.

35 7. A vehicle comprising a lower deck and an upper deck, said lower deck being provided at its front end with separate entrance and exit passageways and having longitudinal seats arranged along that portion of the vehicle adjacent to the inner ends of said passageways, crosswise seats arranged in the rear of said longitudinal seats, a stairway arranged in the rear of said crosswise seats and at one side of the center of said vehicle, and a seat extending along the rear wall of said vehicle and that portion of the side wall thereof opposite said stairway, said stairway entering the upper deck near the rear end thereof and at one side of the center thereof, said upper deck having a seat arranged along the wall of that portion thereof opposite said stairway and having crosswise

seats arranged along both sides of said car in front of said stairway.

8. A vehicle comprising a lower deck and an upper deck, said lower deck being provided at its front end with separate entrance and exit passageways and having longitudinal seats arranged along that portion of the vehicle adjacent to the inner ends of said passageways, crosswise seats arranged in the rear of said longitudinal seats, a stairway arranged in the rear of said crosswise seats and at one side of the center of said vehicle, said stairway entering the upper deck near the rear end thereof and at one side of the center thereof, said upper deck having a seat arranged along the wall of that portion thereof opposite said stairway and having crosswise seats arranged along both sides of said car in front of said stairway.

9. A vehicle of the character described comprising a lower deck and an upper deck, said lower deck having separate entrance and exit passageways at the front end thereof, an officer's station adjacent to said entrance passageway, vehicle controlling devices adjacent to said officer's station, and a stairway within said vehicle at the rear end thereof.

10. A vehicle comprising a lower deck and an upper deck, the lower deck having an entrance and an exit, an inclosed stairway leading from said lower deck to said upper deck, and a doorway controlling the communication of said stairway with one of said decks.

11. A vehicle comprising a lower deck and an upper deck, said lower deck having an entrance and an exit at the front end thereof, an inclosed spiral stairway at the rear end thereof arranged at one side of the longitudinal center of said vehicle, and a sliding door arranged at the lower end of said stairway to control the communication between the same and the lower deck of said vehicle.

In testimony whereof, I affix my signature in presence of two witnesses.
